WARP-BEAM-DRIVEN LETOFF FOR
TEXTILE LOOMS

Charlton Hudson Williams, Columbus, Ga., assignor to Swift Manufacturing Company, Columbus, Ga., a corporation of Georgia

Application August 13, 1946, Serial No. 690,098

10 Claims. (Cl. 139—107)

1

The present invention relates to improvements in warp-beam-driven let-off for textile looms. While there are a great many proposals in the prior art for regulating the delivery of the warp from the warp beam, only the Roper and the Draper mechanisms have had any success in actual practice, and it is well known that both such prior mechanisms employ the principle of driving the warp beam from the let-off, the motion originating in the lay sword or some external mechanism of the loom. The difficulty with such principle lies in the mechanical difficulty of driving the large and heavy warp beam from the relatively small let-off mechanism which must be sensitive to perform its function correctly, and therefore in the old types of let-offs these delicate parts were subject to undue stresses particularly when employed with a warp beam of large diameter in excess of the dimensions for which the loom and the let-off were originally designed for maximum efficiency, the precision of the let-off and its general efficacy suffering under such circumstances.

Another difficulty experienced with the prior mechanisms was that a change in the rate of picks per inch necessitated a gear ratio change in the pinion of the let-off driving the warp beam gear, as a result of which a number of gears of different ratios were required at considerable expense and investment to be kept on hand in the mill adjacent to the loom for substitution along with pick changes. This involved also considerable additional expense in the labor of changing these pinions and of the loss of time in loom operation.

An object of the present invention is to obviate the difficulties above enumerated by reversing the direction of movement so that according to the present invention the warp beam is driven in the usual manner by the tension and draft of the warp and it imparts motion to the let-off under circumstances as controlled by the inherent action of the let-off which is generally of that type known in the art as friction let-offs.

A further difficulty encountered with the prior mechanisms involved the large bulk, the relatively numerous parts and the rather complicated motions of the same, all of which adversely affected the proper maintenance and proper operations of the let-off due to the high humidity conditions prevailing in the weaving rooms of textile mills which has always resulted in the deposit of heavy moisture and lint upon the mechanisms to the disastrous extent of impairing their correct and proper operation.

It is a further object of the invention to sim-

2

plify the construction of let-offs and the operation thereof and to not only reduce the number of parts but to coordinate such parts into a more compact and more easily lubricated mechanism and one less affected by the moisture-matted lint which is bound to settle on all mechanisms in the weaving rooms.

A still further object of the present invention resides in the fact that the weaver may easily 10 let back the warp beam when picking out a defect owing to the fact that the warp beam drives the let-off and is entirely free of any compulsion from the let-off.

A further difficulty with the prior mechanism 15 is that the let-off motions degenerate into jerky and uneven movements in the production of goods having fewer picks per inch, and this lack of uniform smooth motion is communicated to the warp beam because of the let-off drive of the 20 same and results in a lesser proportion of first-grade materials and increases production of second-grade materials.

It is a still further object of the invention to 25 provide an improved let-off motion that is uniformly smooth at all rates of operation to the end that greater uniformity in the production of goods of first class is had with very few seconds.

A still further object of the invention is to provide an improved let-off which admits of adjustment by the simple expedient of rotating a wing nut and does not require the attention of an experienced loom fixer or operator.

A still further object of the invention is to provide an improved let-off that is unaffected by 35 climatic conditions and in which little or no lubrication is required owing to the simplicity of the construction and in which the let-off requires a bare minimum of attention as contrasted with the considerable maintenance required by prior art machines.

With the foregoing and other objects in view, the invention will be described more fully herein-after and more particularly pointed out in the appended claims.

Fig. 31 is a fragmentary side elevation of the brake drum showing the spring bias pawl on an enlarged scale.

Referring more particularly to Figures 1 to 17, inclusive, of the drawings, on the loom side 31 is a ratchet shaft bearing 32 for supporting and journaling a ratchet shaft 33. A ratchet shaft pinion 34 is keyed to the ratchet shaft 33 and meshes with the beam gear 35. On the outer side of the loom side 31 is a friction drum 36, and within the friction drum 36 is a ratchet gear 37. Within the friction drum 36 are two pawls 46 and 47 located diametrically opposite one another and engaging the ratchet gear 37. The ratchet gear 37 is rigidly affixed to the ratchet shaft 33 by

means of a set screw 38. The ratchet shaft pinion 34 is kept in mesh with the beam gear 35 by means of a collar 39, rigidly affixed to the shaft 33 by means of a set screw 40.

The friction drum 36 is kept at a suitable distance from the ratchet shaft bearing 32 by means of a tubular spacer 41. Mounted at a suitable distance forwardly of the ratchet shaft bearing 32 is a tension shaft bearing 42 for carrying a tension shaft 43. On the inner or loom side of the tension shaft 43 at a point substantially close to the end of the tension shaft 43 is rigidly affixed a beam arm 44 which is held rigidly in place to the tension shaft 43 by means of a set screw 45.

Outwardly of the loom side 31, a tension support arm 48 is affixed to the tension shaft 43 by a set screw 49. On the upper end of the tension support arm 48 is mounted a stud or pivot 50 on which rotates a pivotal bearing 51. The bearing 51 slidably supports a tension rod 52. One end of the tension rod 52 carries a hook 53, the other end being threaded to receive a wing nut 54. A helical spring 55 envelops the tension rod 52, one end of said spring abutting the pivotal bearing 51 and the other end of said spring abutting the wing nut 54.

A friction strap 56, having cork or other brake friction block spacers 59 and looped ends 57 and 58, is placed about the friction drum 36. One of the looped ends 57 is slipped over the tension shaft 43 and the other looped end 58 engages the hook 53 on the tension rod 52.

In operation of the improved let-off as applied to the Draper loom, the replenished warp beam 60 is replaced as usual in the loom in a manner to mesh the beam gear 35 with the ratchet shaft pinion 34; this being accomplished by mounting the warp beam 60 in its bearings in the usual manner.

Initially, the set screws 45 and 49 are loosened, and the beam arm 44 is adjusted angularly about the axis of the tension shaft 43 without imparting any rotation to this shaft, the adjustment being counter-clockwise to a point where the foot 62 rides upon the external periphery of the warp mass 61 on the warp beam 60. At this point the set screw 45 is retightened to affix the beam arm 44 to the tension shaft 43.

The tension support arm 48, which is still loose on the tension shaft 43 is now rotated or adjusted in a clockwise direction, as viewed in Figures 1, 8 and 9, through an angular distance which will correspond to the amount of tension, roughly valued, desired to be placed upon the brake band 56 in its embrace of the brake drum 36. The second set screw 49 is thereupon retightened to cause the tension support arm 48 to rotate with the tension shaft 43.

The third step involves rotation of the wing nut 54 in a right-hand direction to cause the same to axially approach the pivotal bearing 51 which now acts as a fixed abutment against which the coil spring 55 may be thus compressed. The reaction of the coil spring from the fixed abutment 51 against adjusting abutment or nut 54 tends to slide the tension rod 52 through the pivotal bearing 51 in a right-hand direction, viewed in Figures 1, 8 and 9. This further draws taut the brake band 56 about the brake drum 36 and adds to the tension of the let-off. The adjustment of the nut 54 on the threaded end portion of the tension rod 52 therefore constitutes a secondary or vernier adjustment on the friction brake of the 75 let-off. The manner in which this adjustment is

actually accomplished is to set the beam arm 44, then to set the tension support arm 48, following which the loom is started and the let-off of the warp from the warp beam 60 is observed as to the freeness, smoothness and evenness of its delivery from the warp beam as demanded by the number of picks per inch in the weaving operation. As the loom is thus preliminarily and empirically operated under observation, the wing nut 54 is rotated in one direction or the other to increase or decrease the compression of the coil spring 55 and thereby correspondingly adjust the frictional tension of the brake band 56 on the brake drum 36. In this way a micrometer adjustment of the frictional brake tension is nicely secured to the end of uniform, even and efficient loom operation irrespective of the number of picks per inch.

As the loom operation proceeds and the warp mass diameter of the warp beam 60 decreases owing to consumption of the warp in the weaving of the fabric, the beam arm 44 which is heavy or weighted falls with depletion of the warp mass periphery and thus causes rotation of the tension shaft 43 and also the entrained tension support arm 48 in a counter-clockwise direction, viewed from Figures 1, 8 and 9. This action causes angular shifting of the pivotal bearing 51 to the left or toward the brake drum 36, thus easing the tension on the brake band 56 and allowing a freer rotation of the warp beam 60 incident to the normal pull and tension on the warp by the heddle and other loom action. It will be noted that the movement of the tension support arm 48 is pivotal about the tension shaft 43 and that there is a secondary pivotal action of the pivotal bearing 51 about the axis of the pivot 50 carried by the tension support arm 48. This may be desirable to preserve alignment between the tension rod 52 and the tangent portion of the brake band 56 with which it connects and with which it will normally be held in alignment by the tension of the spring 55. This alignment is desirable also to prevent binding of the tension rod 52 in the pivotal bearing 51 because as the tension support arm 48 rotates progressively counter-clockwise, the tension of the brake band 56 on the spring 55 will be progressively reduced allowing the spring to react and expand and increase the distance between the abutments 51 and 54, the greater the counter-clockwise rotation of the tension support arm 48. Thus the spring 55 performs a secondary and a double function in relation to the other parts, namely, it tends to take up slack in the brake band 56 automatically as the automatic action of the let-off tends to create such slack in the brake band 56. Thereby, the brake blocks 59 are constantly kept in track on the brake drum 36, and moreover, suddenly large and uncontrolled releases of the brake band 56 are avoided. In other words, the release of the tension of the brake band 56 on the brake drum 36 is extremely gradual incident to this reactive expansion of the spring 55 in the action of the let-off, which aims to give greater freedom of rotation to the warp beam with the progressive decreases in diameter of the warp mass thereon in order to compensate for such differences in diameter from full to empty beam throughout the entire gamut of the operation of the loom. It is noted that once the adjustment is made for a given diameter of warp beam, such adjustment remains true throughout the operation of the loom with subsequent warp beams of the same diameter.

In the event of a flaw in the weaving and it is

found necessary to back down the warp beam 60, it will not be necessary to make any mechanical adjustments. In backing down the warp beam 60, the beam gear 35 drives the ratchet pinion 34 in a direction to cause sliding of the pawls 46 and 47 over the inclined faces of the ratchet teeth.

During rotation of the warp beam, the gears 35 and 34 drive the ratchet gear shaft 33 and therefore also drive the ratchet wheel 37 affixed thereto. Such driving, in the normal operation of the loom, is in a counter-clockwise direction, as viewed in Figure 1, so that the notches of the ratchet teeth interlock and engage with the pawls 46 and 47, thus entraining the brake drum 36 to rotate with the warp beam. Consequently, the rotation of the warp beam in its action of letting off the warp is directly controlled by the value of the friction imposed by the brake band 56 upon the brake drum 36 which carries the pawls 46 and 47. These pawls are spring pressed or biased to engage the ratchet teeth.

It will be observed that the beam arm 44 is constructed with a radial shank 44^a adjacent the bearing 44^b which embraces the tension shaft 43. Outwardly of the shank 44^a, a curved section 44^c of the beam arm 44 connects with the foot 62 which is constructed of a substantial mass of material constituting a gravity weight. The straight section 44^a of the beam arm is desirable to position the weight 62 carried by the curved arm section 44^c to a potential position where it may constantly exercise its gravitational force tending at all time to rotate the tension shaft 43 in a counter-clockwise direction, all as permitted by the warp mass diameter of the warp beam.

Referring more particularly to Figures 1, 6 and 16, it will be noted that the brake drum 36 has flanges 36^a, forming an annular depressed track 36^c for the cork spacers 59 of the brake band 56, and that such drum 36 is carried by a disk or web 36^b, having at its central portion a hub 36^d which is freely mounted over the ratchet gear shaft 33, being held against axial deviation thereon by the set thrust collar 39 at one side and the impingement of the boss 36^e of the drum disk against the ratchet wheel 37. The set screw 38 binds the ratchet wheel 37 to the ratchet shaft 33 and thus constitutes the ratchet wheel 37 as a fixed abutment to take the thrust of the boss 36^e.

It will be noted, particularly from Figure 6, that the supporting disk 36^b is off center with respect to the brake drum 36 in a direction away from the ratchet wheel 37 whereby to provide within the drum a recess which compactly receives the ratchet wheel 37, the brake drum and its supporting disk 36^b thus constituting substantially a housing for the ratchet wheel 37 and enabling a close coupled relationship between these conjointly acting parts whereby the ratchet teeth on the peripheral edge of the ratchet wheel 37 rotate concentrically within a central portion of the brake drum 36, which brake drum is thus enabled to perform a second function of acting internally as a support for the pawls 46 and 47.

As shown more particularly in Figures 6 and 16, lips 36^f extend inwardly from the annulus which is the brake drum 36 at diametrically opposite points and in spaced relation to the disk 36^b for the purpose of receiving the pivot pins 75 on which the pawls 46 and 47 are mounted. These pawls are associated with springs 76 to urge the same into the teeth of the ratchet wheel 37. The pawls have tail pieces 77 projecting circumferentially away from the lips 36^f to be accessible to

manipulation in the assembly and disassembly of the ratchet mechanism.

Referring more particularly to Figure 10 of the drawings, the bearing 42 is a substantially cylindrical bearing carried by a cross bar 78 having the bolt-receiving reinforced band and enlarged ends 79 adapted to receive the bolts 80 when the bar 78 is applied to the inside surface of the loom side 31 as shown in Fig. 2. A reinforced web 81 connects the cylindrical bearing 42 with the bar 78 on that side extending away from the loom side 31.

Referring more particularly to Fig. 12 the arm 48 is shown as carried by a hub 82 which is slidably freely over the tension shaft 43 at the outer side of the loom side 31 in position to abut against the outside end of the bearing 42 as seen in Fig. 2. The arm 48 has an offset portion 48a in order to bring the outer portion of the arm into the approximate plane of the brake drum 36 whereby the tension rod 52 passing through pivotal bearing 51 is in alignment with the brake band 56 and the channel 36a of the brake drum.

Referring more particularly to Fig. 11 the bearing 32 is shown as having a web 83 adapted to extend along the inner wall of the loom side 31 to which it is bolted. A second web 84 has an angularly perforated extension 85 adapted, as shown in Fig. 2, to abut against and be bolted to the loom brace 66. These two webs 83 and 84 provide for attaching the bearing 32 to right angularly related parts of the loom to give strength to the support of the ratchet shaft 33.

This ratchet shaft 33 as shown in Fig. 15 is provided with a keyway 86 corresponding to a similar keyway 87 in the pinion 34 as shown in Fig. 13 whereby a key may be introduced for the purpose of locking the pinion 34 to the shaft 33 as it is by this arrangement that the let-off is driven from the warp beam.

Referring more particularly to Figs. 18 to 25 inclusive a modified form of the invention is shown for use more particularly with a Crompton & Knowles C-4 box loom in which the ratchet wheel, pawls, brake drum and brake band are or may be constructed as heretofore described and which bear the same reference numerals.

The invention in this particular case comprises the means by which one of the looped ends 57 is slipped over a brake arm 63 having an upstanding lip 65; said brake arm being more particularly shown in Fig. 22 as having an angular end 88 perforated to receive a bolt or other fastening by which the arm or bracket 63 is carried outwardly of the loom side 31. After carrying the brake band 56 down beneath the brake drum and up substantially vertically on the rear of the loom, the free end of the brake band is engaged by a hook 89 of an elongated tension rod 90 which extends substantially vertically upward and slidably through a perforation 91 in the diagonally bent end 92 of a tension rod support 64 shown more particularly in Fig. 23. This tension rod support is also provided with holes or perforations 93 for receiving bolts or other fastenings 94 by which the same is affixed to the loom side 31a as shown in Fig. 18 with the same overhanging the brake mechanism. A substantial upper end portion of the tension rod 90 rises above the support 64 in order to accommodate a coil spring 55 the lower end of which engages as a fixed abutment said support 64. The upper end of the rod 90 is threaded to receive a wing or other

nut 54 by which the tension of the spring 55 is nicely adjusted.

Referring more particularly to Figs. 20 and 21 a ratchet shaft bearing 95 is so carried by the loom side 31a that it receives therethrough the ratchet shaft 33a carrying the pinion 34a which meshes with the beam gear 35a. The bearing 95 is carried by a web 96 having a perforated portion 97 adapted to be bolted to the outside of the loom side 31a.

In the operation of this type of loom, the warp beam 60 is placed in its journals so that the beam gear 35a meshes with the ratchet pinion 34a. Initially the warp beam is full and as such demands a slower let-off motion. In order to provide such slower let-off motion increased friction is brought to bear upon the brake drum 36 by the tightening of the wing nut 54 which compresses the spring 55a and tends to draw the elongated tension rod 90 upwardly, thus pulling the friction strap or brake band 56 more tightly about the friction brake drum 36. The degree of tension applied to the brake drum 36 may be determined by the loom operator. The operator may adjust the device to the desired friction degree by making a single simple adjustment which involves merely the tightening or loosening of the tension nut 54a.

Referring more particularly to Figs. 26 through 30 inclusive in which a further modified form of the invention is illustrated applicable to a Crompton & Knowles C-2 loom, the ratchet wheel, pawls, brake drum and brake band may be constructed as a unit as heretofore described and the parts are similarly numbered.

In accordance with the invention one end of the brake band 56 is secured by a clip 67 to a bracket 68. This bracket 68 as shown in Fig. 27 is curved, having its lower end engaged against the loom side, and its upper end meeting with the lower side of the motor platform 69. The bracket 68 may be welded or otherwise affixed to these two loom parts.

The other free end of the brake band 56 is connected to one end of a tension spring 98, the other end of which has a hook 99 which is adapted to pass through any one of a series of holes 100 made in a plate 101. The other end of this plate is similarly engaged by a hook 101 carried by the lower end of a flexible cable 71. The cable 71 extends up and over a pulley 72 carried by a bracket 73 secured to the loom side 31b. The horizontal run of the flexible cable 71 is connected to an elongated tension rod 102 which slides through the loom arches 73 and 74. A wing nut 103 is threaded upon a threaded end portion of the elongated tension rod 102 and abuts against one of the arches 73.

As appears in Figs. 28 and 29, a bearing 104 is shown in Fig. 27 as being carried by the loom side 31b by the use of two angularly divergent supporting arms 105 and 106 which are radial to the bearing 104 and which are spaced axially apart substantially the thickness of the loom side 31b whereby one arm 105 engages upon one face of the loom side and the other arm 106 upon the opposite side of the loom side. The arm 105 lies on the outer face of the loom side 31b and has a perforation 107 for a bolt transversely passing through the loom side 31b. The other arm 106 has a right angularly turned perforated end 108 for abutting against the loom brace to which it is bolted or otherwise affixed.

The ratchet shaft 33b is journaled through its bearing 104 and fixedly carries at one end the

ratchet wheel and at the other end it fixedly carries the pinion 37^b driven by the warp gear 35^b.

In the use of this device, the adjustment is all made from the weavers alley by the simple and single adjustment of the wing nut 103. By rotating this nut in one direction the tension rod 102 is pulled to the left through the arches 73 and 74 thus drawing upon the flexible cable 71 and the adjusting plate 70 to distend the coil spring 98 whereby to put the same under greater tension. This increased tension is transmitted to the brake band 56 by causing the same to more intimately hug the brake drum and to a greater degree to oppose rotation of the brake drum and consequently of the warp beam. By rotating the nut 103 in the opposite direction the coil spring 98 will be permitted to correspondingly contract drawing down upon the plate 70, the flexible cable 71 and proportionately drawing to the right the tension rod 102 through the arches 73 and 74. In other words, the coil spring 98 will keep the nut 103 tightly against the arch 73 at all times.

Although I have disclosed herein only three modifications of the invention it will be understood that such invention is susceptible of physical embodiment in many different forms and I reserve the right to all such modifications and changes as may come within the scope of the following claims.

I claim:

1. In a loom having a side frame with a warp beam rotatably journaled in said side frame and having a head gear, a friction let-off comprising a shaft mounted through the side frame and having portions thereof projecting within and to the outside of said frame, a pinion affixed to the inner portion of said shaft and in mesh with said warp beam head gear, a stop member affixed to the outer portion of said shaft spaced inwardly of its outer end, a friction drum comprising a drum periphery, a web carrying said periphery and an elongated hub centrally of said web and carrying the same and having an internal smooth bore mounted for free rotation on the outer portion of said shaft with the inner end of said hub abutting said stop, said drum periphery extending outwardly from said web a substantial distance to provide a recess totally within the perimeter of the drum periphery and enclosed only at its inner side by said web, the outer side of said recess being completely open across the entire diameter of the drum periphery, and such open side of the recess exposed outwardly free from said frame, a ratchet wheel having a hub adapted to be slid over the outer free end of said shaft and into said recess, means to affix said ratchet wheel hub to said shaft for rotation therewith, pawls pivotally carried by said drum outwardly beyond said ratchet wheel, spring means to urge said pawls into engagement with the outside surface of said drum periphery, and means for adjusting the tension of said friction means about said drum.

2. A friction let-off for textile looms as claimed in claim 1 characterized by the fact that the ratchet wheel is a substantially thin disc which is of a diameter to extend in close proximity to the inner surface of the drum periphery.

3. A friction let-off for looms as claimed in claim 2 further characterized by the fact that the hub of the disc ratchet wheel extends wholly outwardly from the disc to enable the disc to move wholly within the recess and to approach closely the drum web and its hub.

4. A friction let-off for textile looms as claimed in claim 3 in which lips on the outer portion of the drum periphery project into the outer portion of the recess and pivot pins for the pawls mounted in the drum web and in said lips.

5. In a loom having a side frame with a warp beam rotatably journaled in said side frame and having a head gear, a friction let-off comprising a shaft mounted through the side frame and having portions thereof projecting within and to the outside of said frame, a pinion affixed to the inner portion of said shaft and in mesh with said warp beam head gear, a stop member affixed to the outer portion of said shaft spaced inwardly of its outer end, a friction drum comprising a drum periphery, a web carrying said periphery and an elongated hub centrally of said web and carrying the same and having an internal smooth bore mounted for free rotation on the outer portion of said shaft with the inner end of said hub abutting said stop, said drum periphery extending outwardly from said web a substantial distance to provide a recess totally within the perimeter of the drum periphery and enclosed only at its inner side by said web, the outer side of said recess being completely open across the entire diameter of the drum periphery, and such open side of the recess exposed outwardly free from said frame, a ratchet wheel having a hub adapted to be slid over the outer free end of said shaft and into said recess, means to affix said ratchet wheel hub to said shaft for rotation therewith, pawls pivotally carried by said drum outwardly beyond said ratchet

30 wheel, spring means to urge said pawls into engagement with said ratchet wheel, friction means for engaging the outside surface of said drum periphery, means for adjusting the tension of said friction means about said drum, and warp-
35 engaging means, and a common element connecting said warp-engaging means and said tension-adjusting means to which both said means are individually adjustable.

6. The combination of claim 1 further comprising a friction means retainer affixed to the loom side and to one end of said friction means, a long tension rod affixed to the other end of said friction means, a tension rod support affixed to the loom side through which the tension rod movably passes, and means abutting against said tension rod support for subjecting said tension rod and connected friction means to variable degrees of elastic tension.

7. The combination of claim 1 further comprising a clip for securing one end of said friction means to the motor support bracket of the loom, a helical spring connected to the other end of said friction means, a tension adjusting plate connected to said helical spring, a flexible cable connected to said plate, a tension rod slideable to the loom arches, and means for sliding said rod through said arches.

8. The combination as claimed in 1 characterized by the fact that the friction means comprises a brake band and means for applying tension to said brake band, and means movable in response to diminution of the warp of the warp beam for relaxing the tension on the brake band.

9. The combination of claim 5 in which such common element is a rock shaft on which the warp-engaging and the friction-applying means are separately and independently angularly adjustable with means to affix independently said warp-engaging and friction-applying means for adjustment to said shaft.

11

10. The combination of claim 1 further comprising an angularly adjustable arm, a pivotal bearing carried by said arm, a tension rod slidable through said pivotal bearing and connected to said brake band, a nut threaded on said tension rod, a coil spring on said rod between said nut and pivotal bearing, and means for progressively rotating said arm toward said drum.

CHARLTON HUDSON WILLIAMS.
